UNITED STATES PATENT OFFICE.

FRANK L. AIMÉ, OF SPOKANE, WASHINGTON.

ATTACHMENT PLUG.

Application filed December 9, 1921 Serial No. 521,110.

This invention relates to attachment plugs for electrical accessory apparatus, and more specifically it relates to the internal construction of such plugs.

5 It is an object of this invention to provide an improved attachment plug of the sectional or divided type which is particularly adapted for heavy duty and which is positively maintained in normal position against jar-
10 ring and other loosening effects which cause destruction by overheating and short circuits.

Another object of the invention is to provide a rugged two part electrical connecting plug which is capable of carrying relatively heavy currents and which is susceptible of quick manufacture at materially reduced costs.

A further object of the invention is to 20 provide a simple means for locking together at will the various parts of the plug.

Other objects of the invention will be apparent from a reading of the following detailed description.

25 Heretofore attachment plugs for heavy duty accessory apparatus, such as hand drills, large heaters and the like, have been destroyed by becoming overheated or short circuited due to the loosening of the plugs in the sockets 30 by jarring or other vibrations. It is well understood that reduced contact areas require more current to be transmitted through smaller quantities of metal and that under such circumstances the metal becomes overheated and destroyed. Such heating and destruction of the conducting metal in attaching plugs and sockets usually results from the loosening of the joined parts of the plug by the constant vibration of the buildings in 35 which the the heavy duty apparatus is employed or the bodies upon which the sockets are mounted.

40 My invention contemplates an attachment plug which may be affixed in full current conducting relation in a socket and which may be held in such position against vibrations and like loosening causes. In addition I contemplate the production of heavy duty attachment plugs which substantially eliminate fire risks and which may be positively locked in normal operating position.

45 A selected embodiment of my invention is illustrated in the accompanying drawings wherefore,

50 Fig. 1 is a sectional view of an attach-

ment plug showing some of the constructional features thereof.

Fig. 2 is an under plan view of a cap of the plug.

Fig. 3 is a sectional view of the plug taken on the line of 2—2 of Fig. 1.

Fig. 4 is a top plan view of a base portion of the plug.

Figs. 5 and 6 are respectively, plan and elevational views of a shell contact which is incorporated in the base of the plug.

Fig. 7 is a sectional view of a modified plug showing a spring pressed center contact.

Fig. 7^a is a sectional view of the modified plug shown in Figure 7 and taken at right angles to the section in that figure.

Fig. 8 is a sectional view of the modified plug showing a different type of engaging contact.

Fig. 9 is also a sectional view of the modified plug taken on the line of 9—9 of Fig. 8.

Fig. 10 and 11 are respectively a sectional elevational and plan views of an insulating ring, forming a portion of the base.

Fig. 12 is a view in perspective of one of the sliding contacts illustrating an irregular locking edge, and

Fig. 13 is an elevational view of a shell contact incorporated in the modified form of plugs.

Referring to those drawings and particularly to Figs. 1 to 6, inclusive, the preferred attachment plug is shown as comprising a base 1 adapted to be screwed into an electrical socket and a cap 2 provided with suitable electric contacting members and adapted to be thrust into engagement with base 1 and to be locked thereto when desired.

The base 1 consists of the well known parts such as outside contact 3, insulating bodies 4 and 5 made of porcelain or other desirable material, and a central contact 6. The contact 3 has its lower end pressed or formed into screw threads for engagement with the screw threads of a socket, and its upper end is formed with strips 7 for engaging the insulating ring 5. An annular conducting ring 8 provided with a suitable flange 9 held within a bead 10 in contact 3, receives one or more of the contacts carried by the cap 2. The contact 3 as well as conducting current functions to hold together some of the parts of the base.

The central contact 6 may be incorporated in the base in any desired manner which will permit longitudinal movement thereof with

- respect to the other contact of the base. The preferred manner being to form screw threads on its lower portion and to have it engage a stationary screw threaded bushing 11. The lower end of the contact 6 carries a metal washer 12 which engages the central contact of an electrical socket. This washer also functions to limit the upward movement of the contact 6. The top portion 13 of the contact receives one of the contacts carried by the cap and is so formed that it may be rotated by rotating the cap. I have found that by forming slots 14 in portion 13 that a suitable contact of the bayonet type carried by the cap may be inserted in one of slots 14 and rotated to move contact 6 relatively to contact 3. A suitable insulating bushing 15 surrounds portion 13 and is preferably affixed thereto. By extending the top of this bushing above the top surface of the base, I thereby provide another way for moving the central contact 6 longitudinally, as the bushing may be readily rotated by the thumb and finger.
- 25 The cap of the plug consists of an insulator 16 of suitable material, one or more bayonet contacts 17 which engage with ring 8 of shell contact 3, and a central bayonet contact 18 which engages with contact 6. The cap may 30 be constructed of molded material or of pressed metal with proper insulation for the current carrying parts. Contacts 17 have curved portions 19 which engage a bead 20 formed in ring 8 thus providing one means 35 for holding the cap from being snapped out of the base by a slight pull on the connecting cord. Another means for holding the cap in contact with the base is by having the curved portions 19 moved into restricted cavities in insulating ring 5 (see Fig. 3). The contact 40 18 may be constructed in any desired manner, one form being illustrated in Figs. 2 and 3. Although I have illustrated specific forms of engaging means between the contacts in 45 both the base and cap, I wish to be understood as contemplating any form of engagement which permits positive contact and relative movement. Examples of some of these forms will later be described.
- 50 Having now described the constructing of the plug, consideration will be had as to its operation.
- The base 1 is inserted in a socket in the usual manner and screwed into normal position. In order to firmly affix and maintain the base in the socket, the central contact 6 is rotated by rotating bushing 15 by the thumb and finger thus carrying washer 12 into more positive contact with the central contact of the socket; this movement forcing the screw threaded portion of contact 3 into positive contact with the threads of the socket, thus causing a positive frictional engagement between the base and the socket 65 that is not as susceptible of being loosened by

jarring or by other vibrating movements as the prior type of plugs. This positive engagement between the conducting parts of the base and a socket causes the full designed areas of the contacts to positively engage each other and thus eliminate overheating which takes place when only a portion of the desired conducting surfaces are in contact. 70

After the base has been firmly affixed in the socket and ready for operation, the cap 2 75 may be inserted in the base so that the bayonet contact 18 engages slotted portion 14 of contact 6, and the contacts 17 move into positive contact with the shell contact 3. In the event that the ends of contacts 17 have been bent out of their normal position, they are guided into proper contact with shell 3 by the curved edge 21 of the bushing 15 and by the turned up ends of the contacts. 80

After the cap has been thus inserted as 85 illustrated in Fig. 1 it may be rotated to move contact 6 into positive engagement if the base has not already been locked into position, otherwise it is given only a slight rotational movement in order that curved portions 19 of contacts 17 may be carried into cavities under flanges 22 as illustrated in Fig. 3. These flanges prevent the contacts 17 from being drawn away from bead 20, thus locking the cap to the base. The unlocking 90 of the cap is readily accomplished by rotating the cap to the right or left until contacts 17 are free to be withdrawn or to the right when the washer 12 has not been tightly 95 screwed to the center contact of the socket. 100

My invention permits the use of a plug having the minimum amount of conducting metal and it is especially adapted to be employed with electrical accessories which require relatively heavy current for their operation, although it is to be understood that such a plug may be readily employed with other apparatus and may or may not be locked in position depending upon the conditions of operations. 105

As heretofore mentioned the preferred form of plug may be modified. One of the modified forms is illustrated in Fig. 7 wherein there is provided a spring 23 for moving a lower portion 24 of the central contact into engagement with the central contact of the socket. Such a construction permits the base to be affixed in normal position without requiring special manual attention, and it automatically maintains a positive contact should the socket be screwed only part way to its normal position. This modified form of plug prevents overheating under substantially any circumstances. 115

Another modification of my improved attachment plug will be described in connection with Figs. 8 to 13, inclusive. The upper portion of shell contact 3 is provided with separate up-rights 25 which permit the modified bayonet contacts 26 carried by the cap, to be 120 125 130

received between them and the upper portion 27 of the shell. Rotary movement is given to the central contact by rotation of the cap and shoulders 28 of bayonet contacts 26 are 5 carried under lips 29 of insulating ring 5, thus providing a means for preventing the removal of the cap.

Particular reference to Fig. 12 illustrates the bayonets 26 and shoulders 28 which engage the insulating ring 5. The particular construction of this modified insulating ring is shown in Figs. 10 and 11 and illustrates the cut-away portions 30 for the ends of the contact 3 and shows the lips 29 under which 15 shoulders 28 are moved.

Other modifications and changes may be made in the construction herein illustrated, but such modifications and changes are considered as being within the scope of this invention as defined by the limits of the appendant claims.

What I claim is:

1. In an electrical attachment plug, the combination of a base and a cap adapted to be assembled, an electrical contact carried by said base, an electrical contact carried by said cap and adapted to initially engage said base contact as said base and said cap are brought together, and means in said base under which said cap contact may be moved while still maintained in engagement with said base contact to prevent the abnormal withdrawal of said cap without deforming some part of the complete plug.

35 2. In an electrical attachment plug, the combination of a base and a cap adapted to be assembled therewith, two electrical contacts carried by said base, two electrical contacts carried by said cap and adapted to initially engage said base contacts as said base and said cap are brought together, and means in said base under which one of said cap contacts may be moved while still maintained in engagement with one of said base contacts 40 to prevent the abnormal withdrawal of said cap without deforming the cap contact positioned under said means.

3. In an attachment plug, a base provided with an electrical contact which has a curved portion, a cap adapted to be brought into engagement with said plug, an electrical contact carried by said cap, said contact having a curved portion and arranged to engage said curved portion of the base contact to thereby form a means for temporarily holding said base and said cap in assembled relation, said base being provided with a portion under which the curved portion of the contact carried by said cap may be moved while being maintained in engagement with the contact carried by said base to prevent the separation of said contacts.

4. In an attachment plug a base provided with separate electrical contacts, a cap adapted to be brought into engagement with said

base, separate electrical contacts carried by said cap and arranged to engage the contacts of the base, one of the contacts carried by said cap being curved to engage a curved portion of one of the contacts of said base to thereby form a temporary locking means between said cap and said base, said base being also provided with a projection under which said curved contact of said cap may be moved while being maintained in contact with the curved contact carried by said base, said projection acting to prevent the contacts from being separated without deforming the curved contact of said cap.

5. In an attachment plug a base provided with two electrical contacts separated by insulating material, a cap adapted to be brought into engagement with said base, two separate electrical contacts carried by said cap and arranged to engage the contacts in said base, one of the contacts carried by said base being provided with a beaded portion, one of the contacts carried by said cap being adapted to engage the beaded contact of said base and being provided with a beaded portion for engagement with the beaded portion of the base contact to thereby temporarily lock said cap to said base, said base being provided with inwardly extending shoulders under which the beaded portion of the cap contact may be moved to substantially resist the movement of said cap from said base.

6. In an attachment plug a base provided with a screw threaded contact mounted on the outside thereof, a central contact carried by said base and constructed so as to have relative movement to said screw threaded contact, a resilient means for biasing said central contact outward, said two contacts arranged to engage contacts in an electric light socket when normally positioned therein thereby forcing said central contact somewhat back into said base and to thereby cause said screw threaded contact to positively engage the corresponding contact of said socket, the other end of said screw threaded contact being extended to the interior of said base and being provided with a beaded portion, a cap arranged to be assembled on said base, contacts carried by said cap to engage said two contacts of said base, one of said cap contacts being beaded to engage the beaded portion of said screw threaded contact extensions, and a shoulder associated with said base and extending inwardly over a part of the beaded portion of said screw threaded contact extension, said shoulder arranged to prevent the withdrawal of said cap from said base.

7. In an attachment plug the combination of a base, two contacts carried thereby and separated by an insulating material, one of said contacts being constructed to be moved longitudinally to the other contact, resilient means for controlling the movement of said

contact, a cap arranged to be moved into contact with said base, and contacts carried by said cap and insulated from each other and adapted to engage the contacts in said base, means for temporarily locking said contacts in engagement, and means for locking said contacts against separation without deforming one of them after they have been moved relatively a predetermined distance while 10 still being maintained in engagement.

8. In an attachment plug the combination of a base member provided with a screw threaded contact mounted on the outside thereof and having an extension to the interior of said member, said extension being provided with a beaded portion, a central contact carried by said base member and extending outwardly therefrom, spring means for moving said contact outwardly, a cap member provided with two electrical contacts insulated from each other, one of said contacts

being provided with a beaded portion, said cap member arranged to be placed in engagement with said base member and to have the contacts carried thereby engage the contacts 25 carried by said base member so the two beaded contacts engage each other, said base member being so constructed as to permit the cap to be rotated 360° while said contacts are in engagement, and a shoulder carried by said 30 base and being so positioned as to extend over the beaded portion of the extension of said screw threaded contact for a portion of the 360° thereby forming a means to prevent the separation of said cap from said base when 35 the beaded contact carried by said cap is under said shoulder.

Signed at Spokane in the county of Spokane and State of Washington this 3rd day of December, A. D. 1921.

FRANK L. AIMÉ.
